DESIGN FOR A CHAIR

Sam Belz, Memphis, Tenn.

Application March 7, 1945, Serial No. 118,301

Term of patent 3½ years

(Cl. D15—1)

To all whom it may concern:

Be it known that I, Sam Belz, a citizen of the United States, residing at Memphis, in the county of Shelby and State of Tennessee, have invented a new, original, and ornamental Design for a Chair, of which the following is a specification, reference being had to the accompanying drawing forming part thereof.

Figure 1 is a view in perspective at one side of a chair embodying my new design; and

I claim:

The ornamental design for a chair, substantially as shown.

SAM BELZ.
